UNITED STATES PATENT OFFICE

HARVEY RIDGE, OF IOLA, KANSAS

PAPER PASTING MACHINE

Application filed September 4, 1929. Serial No. 390,391.

The present invention relates to apparatus for applying an adhesive coating to one surface of paper or similar material wound into a roll, and the primary object of the invention is to provide an improved pasting machine for applying paste to wall paper or the like.

A further object of the invention is to provide an improved paste applying device for wall paper embodying an arrangement whereby an even coating of paste is applied to one surface of the paper and drawn in strips of any length from the device.

A further object of the invention resides in the novel cutting means allowing cutting of the pasted paper to any desired length and retaining the cut end of the paper in a position to be readily grasped for drawing further lengths of paper from the supply roll.

A further object of the invention resides in the provision of a pasting machine for wall paper and the like, adapted to be positioned upon one end of a paper hanger's table so as to permit relatively long lengths of pasted paper to be drawn from the machine and folded in the usual manner preparatory to hanging.

A still further object of the invention is to provide a device of this character which is of extremely simple construction, one allowing easy and thorough cleaning of the paste container, and one which will not tilt as the paper is being drawn from the machine.

Other objects and advantages of the invention will be apparent during the course of the following detailed description, taken in connection with the accompanying drawings forming a part of this specification and in which drawings:

Figure 1 is a top plan view of the pasting machine showing fragmentary portions broken away for illustrating details of construction.

Figure 2 is a view part in side elevation and part in longitudinal section showing the manner in which the paper is fed thru the pasting rollers.

Referring to the drawings in detail, and wherein similar reference characters designate corresponding parts thruout the several views, the improved paper pasting machine

has been shown including a box-like frame or casing 5 having a flat bottom wall 6, vertical side walls 7 and a rear end wall 8. The frame 5 may be formed from sheet metal or any other suitable material and each side wall 7 is provided adjacent the rear wall 8 with an upwardly projecting extension 9 the forward edges of which are preferably inclined and extend to a point below the upper edges of the side walls 7 providing notches or recesses 10 in the upper edge of each side wall at the forward ends of the extension plates 9. The forward or front end of the frame 5 is left open and at the forward end of each side wall 7 is formed an upstanding arm 11 forming bearing mountings for a removable roll supporting shaft 12, adapted to support a roll of wall paper 13 between the forward ends of the side walls 7.

Secured with a sealed joint between the side walls 7 is an upwardly and rearwardly inclined plate 15 the forward lower edge of which is secured with a sealed joint to the bottom wall 6. The rear upper end of the inclined plate 15 extends slightly beyond the forward edges of the recesses 10 at a location spaced below the upper edges of the side walls 7 as clearly shown in Figure 2. This rearwardly inclined plate 15 aside from forming a guide for the paper unwound from the roll 13, forms a paste reservoir or container 16 for receiving paste adapted to be applied to one surface of the wall paper.

Fixedly mounted upon a shaft 17 suitably journaled in the side walls 7 slightly rearward and below the recesses 10 is a paste applying roller 18 arranged to have its lower portion rotate in the paste contained in the reservoir 16. The roller 18 is arranged to project slightly above the upper rear end of the inclined plate 15 and below the top edges of the side walls 7. By observing Figure 2 it will be seen that with this arrangement that the paper will be guided between the side walls 7 over the upper side of the roller 18 so that paste adhering to the circumference of the roller 18 will be applied to one surface of the paper passing over the roller.

A wiper is provided for removing excess paste from the roller 18 and this wiper is

preferably in the form of a wiping brush including a brush bar 19 mounted between the side walls 7 beneath the rear portion of the inclined plate 15, and which brush bar carries suitable tufts of bristles 20 arranged in wiping engagement with the circumference of the roller 18.

Fixedly secured upon a shaft 22 journaled in the side walls 7 rearwardly and above the 10 pasting roller 18 is a return roller 24 the circumference of which is spaced slightly from the circumference of the roller 18. This roller 24 aside from serving to retain the paper in contact for a portion of the 15 circumference of the pasting roller 18 serves to return the paper passed thereabout to a direction extending above the supply roll 13 with the pasted side of the paper uppermost.

Mounted upon one projecting end of the 20 pasting roller shaft 17 is a pinion 26 for meshing with a pinion of like diameter 27 fixed to a projecting end of the shaft 22 on which the return roller 24 is mounted. This positive drive coupling between the rollers 18 and 24 insures rotation of the pasting roller 18 when a pull is exerted on the pasted portion of paper 28.

Cutting means is provided for cutting off desired lengths of the pasted paper, and this 25 cutting means consists of a pivoted U-shaped cutter mounted to be swung into and out of a cutting position. The cutter includes a cutter bar or blade 30 connected between arms 31 pivotally mounted as at 32 to the 30 outer sides of the extension plates 9. The blade 30 is of a length slightly greater than the width of the frame 5 and the arms 31 are of such length that when the cutter is 35 swung into a cutting position as shown in dotted lines in Figure 2, the cutting edge of the blade will be disposed above the rear edge portion of the inclined plate 15. In full lines in Figure 2 the cutter has been shown in its inoperative position resting upon the 40 upper edge of the side walls 7 rearwardly of the extension plates 9. The recesses 10 will permit of the cutting edge of the blade 30 engaging the upper edge of the plate 15 so that the paper may be readily torn on a 45 line along the blade.

An expansion coil spring 35 preferably 50 encircles the shaft 12 between one end of the roll 13 and one of the arms 11 for normally urging the roll into engagement with one of 55 the side walls 7. This arrangement insures straight feeding of the paper along the inner surface of one of the side walls.

The pasting machine may be of about 60 twelve inches in length and in use is intended to be placed upon the upper side of a paper hanger's table adjacent one end thereof. The shaft 12 may be removed and inserted thru the roll of paper to be pasted and after 65 which the shaft is mounted in the arms 11 with the roll unwinding from its lower side.

The end of the paper is trained over the roller 18 and beneath and about the roller 24 which returns the end 28 above the roll 13. With 70 paste in the reservoir 16 it will be seen that when a pull is exerted on the end 28 that an even coating of paste will be applied to one surface of the paper. After the paste has been applied to a suitable length of the paper, the cutter is swung forwardly engaging the pasted paper end 28 and pressing the 75 same upon the run of paper 40 along the rear upper side of the inclined plate 15. The paper may then be torn along the blade 30 leaving a short run of paper extending from the blade upwardly over the roller 24 which 80 may be easily grasped for drawing further lengths of paper from the roll 13. This short run of pasted paper is shown by the dot and dash line 42 in Figure 2.

The inclined plate 15 aside from permitting increased capacity of the paste reservoir 16 provides a rest for the blade 30 during the cutting operation, permits of a guide way being formed between the roll 13 and pasting roller 18 for the run of paper 40, and also permits proper mounting of the wiper brush.

Since the upper side of the reservoir 16 is 90 open it will be seen that the reservoir may be very easily refilled and that thorough cleaning of the paste reservoir may be readily accomplished. By having the paste reservoir and pasting and cutting devices arranged at the rear portion of the frame 5 it will be 95 seen that there is little likelihood of the machine tilting upwardly at its rear end when a pull is being exerted on the paper in a direction forwardly of the machine.

From the foregoing description it will be 100 apparent that a novel and improved construction for paper pasting machines has been provided which is of extremely simple and durable construction and one which may be easily operated for applying an even coating of paste to any desired length of wall paper.

Changes in detail may be made to the form 105 of invention herein shown and described, without departing from the spirit of the invention or the scope of the following claims.

I claim:

1. A pasting machine of the class described 110 comprising a frame including parallel side walls, a rear wall and a flat bottom wall, a partition plate mounted in a rearwardly inclined position between the side walls and having its rear upper end spaced below the upper edges of the side walls, said side walls being notched at points aligning with the rear end of said plate, a pasting roller mounted 115 between the side walls at the rear end of the plate below the upper edges of the side walls, a return roller mounted in vertical rearwardly offset relation to the pasting roller, wiper means for removing excess paste from the pasting roller, said pasting roller having its upper extremity spaced below the 120

125

130

upper edges of said side walls, means for supporting a roll of paper between the side walls at the forward end of the frame, said paper to be trained over the pasting roller and about 5 and forwardly of the return roller, and a cutter pivotally mounted in the side walls embodying a cutter bar movable into the notches in the side walls for severing the paper above the rear end of said partition plate.

2. A pasting machine of the class described comprising a frame including parallel side walls, a rear wall and a flat bottom wall, said side walls adjacent their rear ends each being 10 provided with an upwardly projecting extension plate and at the forward end of each plate being recessed below the top edges of the side walls, a rearwardly inclined partition plate supported between the side walls 15 and providing a paste reservoir in the rear portion of the frame, said partition plate having its rear end portion projecting rearwardly beyond the forward edges of said recesses, a pasting roller mounted in the reservoir, a return roller mounted in vertical 20 rearwardly offset relation to the pasting roller, means for supporting a roll of paper between the side walls at the forward portion of the frame, and cutter means including 25 side arms pivotally mounted upon the outer sides of said extension plate and a straight cutter bar movable into said recesses for engagement with the paper above 30 the rear end portion of said partition plate 35 when the cutter arms are swung forwardly.
